Specification for Design.

Patented June 7, 1921.

Application filed November 12, 1920. Serial No. 423,738. Term of patent 3½ years.

To all whom it may concern:

Be it known that I, ADOLPH A. HENKEL, a citizen of the United States, residing at Chicago, in the county of Cook and State of Illinois, have invented a new, original, and ornamental Design for Electric-Lighting Devices, of which the following is a specification, reference being had to the accompanying drawing, forming part thereof.

The figure is a perspective view of an electric lighting device showing my new design.

I claim:

The ornamental design for an electric lighting device as shown.

ADOLPH A. HENKEL.
